UNITED STATES PATENT OFFICE.

GRACE DAILEY PRESTON, OF LAKESIDE, OHIO, ASSIGNOR OF TWO-FIFTHS TO ARTHUR G. SMITH, OF ELYRIA, OHIO.

FASTENING DEVICE.

1,374,680.

Specification of Letters Patent. Patented Apr. 12, 1921.

Application filed July 30, 1919. Serial No. 314,292.

To all whom it may concern:

Be it known that I, GRACE DAILEY PRESTON, a citizen of the United States, residing at Lakeside, in the county of Ottawa and

5 State of Ohio, have invented certain new and useful Improvements in Fastening Devices; and I do hereby declare the following to be a full, clear, and exact description of the invention, such as will enable others 10 skilled in the art to which it appertains to make and use the same.

This invention relates to fastening devices for securing together the edges of garments and the like. By way of example, my invention finds particular use in connecting the 15 opposite edges of ladies' waists and the like, which, for the most part, have in the past been connected by buttons, hooks and eyes or snap fasteners, which are sewed to the 20 edges of the garments. As is well known, these devices are open to many objections, the principal of which results from the rough handling received during laundrying, and which results in breaking the buttons 25 and crushing or otherwise deforming the hooks or snap devices, so that they will no longer perform their functions. These injuries have increased in number and in 30 magnitude as laundrying machinery has come into more general use, and are of such a nature as frequently to incapacitate the fastening devices for further use, and make it necessary to remove them and sew others on their place.

35 One of the objects of my invention is to provide fastening means which can be conveniently and readily detachably connected to the edges of garments, and which will at the same time properly serve the function of 40 temporarily connecting the edges of the garments together.

Another object of the invention is to produce snap devices that can be applied to the edges of garments in such a way as to 45 render them entirely invisible when the garment is secured in place.

Other objects will appear in the following description, reference being had to the drawings, in which—

50 Figure 1 is an edge view of one of the snap devices.

Fig. 2 is a side view of the snap device shown in Fig. 1.

Fig. 3 is an edge view of a complementary snap device.

Fig. 4 is a side view of the device shown 55 in Fig. 3.

Fig. 5 is a view of garment edges having the snap devices of Figs. 1 and 3 applied thereto.

Fig. 6 is a view of a garment or fabric 60 having the attached clasps in superposed position for snapping the edges together.

Fig. 7 is a side view of a modified clasp.

Fig. 8 is an edge view of the clasp shown in Fig. 7.

Fig. 9 is a clasp complementary to the one shown in Fig. 7.

Fig. 10 is an edge view of the clasp shown in Fig. 9.

Fig. 11 is a view of garment edges having 70 the clasps of Figs. 7 and 9 attached and in position for snapping together.

Fig. 12 is a view of garment edges secured together by the snap fasteners of Fig. 11.

Fig. 13 is an elevation of a modified form 75 of clasp.

Fig. 14 is an edge view of the clasp of Fig. 13.

Fig. 15 is a plan view of the fastener shown in Fig. 14.

Referring to the drawings, one embodiment of my improved snap fasteners is shown in Fig. 1 and consists of wings 1 and 2 of somewhat triangular shape joined at their base lines 3. The wing 1 may have a 85 plurality of prongs *a*, *b*, *c*, *d* and *e* to enable the wing to enter beneath the hem of a garment to better advantage. The central prong *c* has a snap fastener 4, which in this instance is shown as a socket member, and 90 the wing 2 may have a headed stud 5 adapted to snap into the eye or socket 4 when the clasp is bent into position around the garment edge, as is shown in the right-hand side of Fig. 5. The wing 2 also has a member of a snap fastener, which may be in this 95 instance a headed stud 6, adapted to snap into a complementary fastening socket in another clasp secured to the other edge of the garment, as later described.

100 In Figs. 3 and 4 the complementary snap

fastener is shown, which consists of triangular wings 7 and 8 joined together at their base line 9. The wing 7 may have a headed stud 10, which is adapted to snap into an eye or socket 11 on the wing 8 when the clasp is bent into position around a garment edge, such as is shown in the left hand side of Fig. 5. The wing 7 has a socket member 12 adapted to receive the headed stud 6 of the complementary clasp shown in Figs. 1 and 2.

To attach the clasp shown in Figs. 1 and 2, it is bent into U-shaped form and the prongs *a*, *b*, *c*, *d* and *e* of the wing 1 are inserted under the hem 13 of the garment edge 14 of Fig. 5. The clasp automatically loosens the threads of the hem sufficiently to permit this, or the threads may be otherwise loosened. The stud 5 then is snapped into the socket 4, pushing the cloth down through without piercing it. The clasp shown in Figs. 3 and 4 is next bent into U-shaped form and placed over the inner edge 15 of the garment and the stud 10 of the wing 7 snapped into the socket 11 of the wing 8, the cloth or fabric being pushed into the socket without being pierced.

With the clasps attached to the garment edge as described, the edge 14 of the garment may be pulled over the edge 15 (under it as shown in Fig. 5), and the stud 6 snapped into the socket 12. The garment edges are thus attached together, and since the edge 15 is the underlapping one and the edge 14 the overlapping one, the snap fastener will be entirely hidden from view and the garment will be fastened securely together by invisible fasteners.

Fig. 6 is taken at right angles to the showing in Fig. 5 and the position of the clasp will be clear by referring to it. The wings of the clasp are shown slightly separated for purposes of illustration, but it will be understood that in use the wings will be tightly pressed against the fabric between them. In this figure the clasps are shown superposed and by pushing them together the edges will be secured together.

To detach the fasteners, all that is necessary is to unsnap the wings and remove them from the garment, which permits the garment being laundered without endangering the fastening devices. The clasps or fastening devices may, therefore, be attached and detached whenever desired, without injuring the fabric or without impairing the clasp.

In Figs. 7 and 8 I have shown a second embodiment of my invention. In this modification one wing of the clasp has a plurality of narrow prongs 16 reaching substantially to the base line or juncture edge 3. The other wing 17 is shown more or less rectangular in shape, by way of ex-

ample, and it has a socket member 18 of a clasp adapted to snap with a stud of the complementary clasp, shown in Figs. 9 and 10. In the clasp of Fig. 9, the wing 19 may have a plurality of short prongs 19'. The wing 20, which is integrally joined to the wing 19, as in the first described modification, has a headed stud 21 adapted to snap into the socket 18 of the complementary clasp.

The clasp of Fig. 7 is bent substantially into U-shaped form and the slightly curved prongs 16 inserted between the seams of the hem 22 (Fig. 11) until the ends 23 of the prongs 16 pierce the edge 24 of the hem. They are then bent over the end of the clasp 17, as shown. The clasp of Fig. 9 may be similarly bent into more or less U-shaped form and inserted over the entire edge 25 of the garment and the prongs 19' are bent through the fabric and over the wing 20. The wings 19 and 20 may have indentations 34 to receive the curved points 23 of the prongs.

The garment edges with the clasp attached are shown in Fig. 11 in superposed position, and by pressing the edges together the stud 21 will enter the socket 18 and secure them together. In this connection it should be noted that the garment edge having the hem 22 is the outside one, so that the clasps are entirely hidden from view, as shown more clearly in Fig. 12.

It will be apparent that the fasteners shown in Figs. 7 and 9 may be attached and detached from the garment edges without injuring the fabric further than by making slight perforations where the prongs pierce the cloth. These prongs are small, so that the perforations will automatically close as soon as the clasps are removed from the goods.

In Figs. 13 and 14 I have shown a still further modification. The clasp consists of a body portion 35, which may be of various shapes, having serrated edges to grip the fabric or other material between the wings when the clasp is bent along the line 36. The serrations may extend along the ends only, or along the entire periphery of the clasp. However, by way of example, I have shown a clasp in the drawing with a small portion at 37 near the middle where there are no serrations.

The clasp in Figs. 13 and 14 is shown with a stud 38 which will act as a snap fastener to coöperate with a socket member in the complementary clasp. This embodiment, as well as the others, can be snapped around the entire edge, if desired, as shown at 25 in Fig. 11, or it may be inserted under the hem, by loosening the stitches, as at 22 of such figure.

In Fig. 15 I have shown a further modifi-

cation in which one of the wings has a plurality of prongs *f*, *g*, *h*, each with serrations. In punching this clasp the teeth may be staggered with respect to those of adjacent edges, if desired, so that a clasp of minimum width will be secured and a saving of metal will result. In this modification the prongs of the wing can be readily inserted under the hem, as indicated in the 10 upper part of Fig. 6, with respect to the embodiment first described.

While I have described my improvements in connection with garments, this has been by way of example only, and it is capable 15 of use as fastening means for the edges of tents, tarpaulins, automobile curtains, military equipment, etc.

The sockets and studs in my clasps may be made similar to those shown and described in my copending application filed Apr. 6, 1918, Serial No. 227,002, or they may be made in various other ways, either by integral punchings or separate attached parts.

Having described my invention, what I claim is:

1. A garment having overlapping and underlapping edges to be attached and detached, the overlapping edge having an inwardly folding strip forming a hem, a metal clasp having a pronged wing passing beneath the hem and another wing over the same, a snap fastener on said last mentioned wing, means for securing the wings in place 30 around the hem, a second metal clasp having wings passing around the said underlapping edge and a snap fastener on the outer wing of the last mentioned clasp to coöperate with the first-mentioned snap fastener, 35 whereby the edges of the garment may be secured together with invisible fasteners.

2. In fasteners for flexible material, a metal clasp consisting of overlapping wings joined together at one end, one wing having 45 one or more prongs adapted to pass beneath the hem on the edge of said material, the ends of said prongs adapted to bend over the free end of the adjacent wing to attach the clasp to said hem with the free ends of 50 the wings toward the edge of the material, a second metal clasp consisting of wings similarly joined at one end, one of the wings of said second mentioned clasp having prongs adapted to bend over the other wing to clasp 55 between the wings another edge of the flexible material with the joined ends adjacent to the edge thereof, whereby the two clasps superpose when the edges of the material are brought together and snap fastening 60 means on the contacting faces of said clasp to attach and detach the said edges.

3. A garment having overlapping and underlapping edges to be attached and detached, the overlapping edges having an in-

wardly folding strip forming a hem, a metal 65 clasp having a pronged wing passing beneath the hem and another wing over the same, a snap fastener on said last mentioned wing, means for securing said wings in place, a second metal clasp having wings 70 passing around the said underlapping edge and a snap fastener on the outer wing of the last mentioned clasp to coöperate with the first mentioned snap fastener whereby the edges of the garment may be secured together 75 with invisible fasteners.

4. In fasteners for flexible material, a metal clasp consisting of overlapping wings joined together at one end, one wing being adapted to pass beneath the hem on an edge 80 of said material, one of said wings having fastening means to attach the clasp to the hem on the inside of said material, with the free ends of the wings toward the edges of the material, a second metal clasp consisting 85 of wings similarly joined at one end, one of the wings of said second mentioned clasp having fastening means adapted to secure the other wing to clasp around another edge of the flexible material with the joined ends 90 adjacent to the edge thereof, whereby the two clasps superpose when the edges of the material are brought together with both clasps hidden from view, and snap fastening means on the contacting faces of said clasp to attach and detach the said edges.

5. In fasteners for flexible material, a metal clasp consisting of overlapping wings joined together at one end, a plurality of serrations on the edges of said wings adapted 100 to clasp the edge of said material therebetween, and a snap fastener on one wing of said clasp.

6. In a device of the class described, a pair of metal clasp members, each of the said members comprising a normally flat strip of sheet metal having prongs at one end, said sheet being flared at a point intermediate of the ends to provide superposed wings, the said prongs being a part of one 105 wing, the other wing being serrated, whereby a piece of flexible garment material may be securely clamped between the two wings, coöoperating snap elements on a wing of each of the clasps and adapted to unite the clasps 110 together when they are pressed together.

7. In a fastener for uniting separated portions of flexible garment material, a metal clasp adapted to be clamped onto each portion, said clasp comprising superposed 120 wings, the garment material portion being held between the wings, one of the said wings comprising a plurality of sharpened prongs, the other of the said wings being serrated, said prongs and the serrations on the opposite wing coöoperating to securely hold the clasp in place on the flexible material and coöoperating snap fastening elements 125

on a wing of each of the said fasteners adapted to be sprung together to unite the said clasps.

8. In fasteners for flexible material, a pair 5 of coöperating metal clasps, each consisting of overlapping wings joined together at one end, a plurality of serrations on the edges of

said wings adapted to clasp the edge of said material therebetween, and a snap fastener element on one wing of each said clasp. ¹⁰

In witness whereof, I have hereunto signed my name this 24th day of July, 1919.

GRACE DAILEY PRESTON.
